UNITED STATES PATENT OFFICE.

HOWARD F. MARSTON, OF DAYTON, OHIO, ASSIGNOR TO MERCANTILE CORPORATION
OF DAYTON, OHIO, A CORPORATION OF NEW YORK.

COMPOSITION CARRIER OR HOLDER.

1,214,051.

Specification of Letters Patent. Patented Jan. 30, 1917.

Application filed January 19, 1916. Serial No. 72,913.

To all whom it may concern:

Be it known that I, HOWARD F. MARSTON, a citizen of the United States, residing at Dayton, in the county of Montgomery and State of Ohio, have invented certain new and useful Improvements in Composition Carriers or Holders, of which the following is a full, clear, and exact description.

This invention relates to certain new and useful improvements in holders or carriers for composition, of the type shown, described and claimed generically in my copending application Serial No. 49,882. In the application above referred to there was shown a composition carrier which was adapted to be slid to central position for printing and to be bodily withdrawn to one side of the machine when it is desired to change or clean the type or composition.

In printing work, particularly in the manufacture of envelopes, speed is of primary importance. With the holder, previously referred to, it was necessary to stop the machine when it was desired to slide the holder to type changing position, and the machine had to be kept stopped until the type changes had been made and the holder replaced in printing position. With the improved holder which is the subject matter

of this application the holder is made double and the two parts of the holder are so associated with one another that when one part is rotating in printing position the other part of the holder is without the frame of the machine and stationary. This enables the operator of the machine to load one holder while the machine is in operation and in this manner the duration of the stops is decreased and the output of the machine cer-

respondingly increased. With the improved double holder the only time the machine need be stopped, is that necessary to actually slide the holder axially in the frame of the machine. In operating envelop machines equipped with the double form of holder, by arranging the machines side by side, it is possible to station the operators between the machines and in this way one operator can assist the operator of the adjacent machines in changing slugs or composition. In this way the output of the battery of machines may be increased.

It will be understood that my invention is not limited in its use to envelop machinery, since the improved holders are equally val-

able in other printing machines where frequent type changes are necessary.

In the drawing, Figure 1 shows a central sectional view of my improved holder. Fig. 2 is a top plan view. Fig. 3 shows a detail sectional view, taken on line 3—3 of Fig. 1, which shows the manner in which the slug holder is properly aligned with the driving gear. Fig. 4 shows a side view of the printing machine frame with the holder in place. This view also shows the means for releasing the holder from the opposite side of the machine. Fig. 5 is a detail view taken on line 5—5 of Fig. 1, and looking in the direction of the arrow. In this view certain parts are shown in dotted lines to show their corresponding relative positions when the right hand holder is in "in" position. Fig. 6 is a detail view showing the right hand handle and associated parts. Fig. 7 is a bottom view of the right hand holder shown in Fig. 1.

In this invention the paper feeding rolls, platen, ink roll and other parts are omitted. Such parts are, however, well known in the printing art and reference may be had to my copending application Serial No. 49,882 for an illustration of a specific use of this holder. Specific details of the type composition or slug holding mechanism are also given in this copending application.

In Figs. 1 and 2, 10 and 11 represent the side frames of a printing machine. These frames are axially bored to provide bearings for the mandrel, which I will also term a slug carrier or holder or a composition carrier or holder. It will be understood that linotype slugs, type slugs, plate, composition, dies, etc., may be used on this holder or carrier. A driving gear 12 is journaled on the side frame 11. The left hand holder, which I will hereafter designate by the character 14, is practically identical with the holder shown in my copending application. I will however herein give a brief description of this holder 14. The body of the holder is slotted to receive type or composition 17, which composition is secured in position on the holder, by a cam abutment at the right of the type and by a camming member 18 having a tapered nose to engage the type and normally pressed against the type by the spring pressed plunger 19.

To release the type, I provide a handle 20 which is provided with a nose to contact

with an axially placed pin 21 in the holder. When it is desired to operate the handle to release the type slugs, a latch 65 is first released from engagement with a hook 66. 5 This catch 65 is normally held in engagement with the hook 66 by means of a spring, the latch being pivoted in the handle 20. A plunger 67 is longitudinally mounted in the handle 20. By pressing upward upon the 10 button on the lower end of this plunger, the spring pressed latch will be rocked in a clockwise direction about its pivot and be released from hook 66. Thereafter the handle 20 can be swung in a clockwise direction. 15 On swinging the handle 20 in a clockwise direction the pin 21 is forced to the left, thus rocking the camming member 18 counterclockwise against the action of the spring pressed plunger 19 and thereby releasing 20 the type or slugs. Handle 20 is mounted upon the outer face of a bearing sleeve 23 which is revolubly mounted on a stub shaft projecting from the body portion of the mandrel. Bearing sleeve 23 is also adapted 25 to slide into and seat in the bearing 25 of side frame 10. To hold the holder 14 in "in" position, I provide a cap screw 26 which extends outward from frame 10 and which is adapted to engage a camming projection 30 of sleeve 23 when it is desired to lock the left hand holder in "in" position. This construction is fully described in my copending application above referred to. It is sufficient to say that the locking is brought about 35 by rocking the handle 20 about the center of the carrier as an axis which serves to engage the cap screw 26 with a cam edge on the sleeve 23. To unlock the carrier the handle is given a reverse movement which 40 alines the cap screw with a notch in the bearing sleeve 23. Thereafter the carrier may be withdrawn in an axial direction laterally of the frame 10—11.

It will be understood that the slug securing means on the right hand holder, (which I will designate 15) is a duplicate of the slug securing means on the left hand holder. A similar cap screw 27 is used which extends outward from frame 11 to lock the 50 right hand holder in "in" position. This cap screw co-operates with a cam edge and notch on an outer annular member 28 of the holder 15 in a similar manner to the corresponding parts on the left hand holder.

55 *Driving connection to left hand holder 14.*—Extending from the body portion of the left hand holder and integral therewith, is a shaft 29 which extends to the right and which is secured by means of a pin 30 to 60 sleeve 31 which carries the tapered cam abutment for the slugs, and by means of the same pin 30 to a bearing sleeve 32 which rests in a bearing in the right hand side frame 11 when the left hand holder is in "in" position, 65 as shown in Fig. 1. *Integral with the bear-*

ing sleeve 32 is a spur gear 33, which gear enmeshes with the driving gear 12, when the left hand holder 14 is in "in" position. The outside diameter of the teeth of this gear 33 is slightly less than the outer diameter of the bearing sleeve in order that this gear 33 may pass through the bearing in the side frame when the holders are shifted.

70 *Construction of right hand holder.*—When right hand holder 15 is in outer position (shown in Fig. 1) it is necessary that this holder remain stationary with respect to the holder 14. Otherwise it would be impossible to change the type or slugs when the machine is in operation. To this end the body portion 34 is provided with a stub shaft 35 which stub shaft is rigidly secured to the body portion of the holder and to sleeve 36 by means of a pin 37. This stub shaft has integral therewith an enlarged circular head 38 which is revoluble in a recess in sleeve 32. Bearing sleeve 39 is integral with sleeve 36 and is adapted to fit in the bearing in the left hand frame 10 when the right hand holder 15 is in "in" position. The above 80 described construction permits either the right or left hand holder to rotate independently of one another and consequently it is possible to change slugs on the accessible holder, which is stationary while the 85 holder which is in "in" position is rotating.

85 *Construction for alining and timing the holders.*—The holders 14 and 15, being independently rotatable with respect to each other, it is necessary that some means be 90 provided for properly alining the holder and the driving gear, when the holder which is in "out" position is shifted to "in" position. Otherwise the type would be in improper angular position and the printing 105 would occur at the wrong place on the paper, or possibly there would be no printing at all. For this purpose the following instrumentalities are provided. The right hand holder 15 from end to end is provided with a number of longitudinal slots 40, which slots are 110 in the form of gear teeth. These teeth are of such dimensions that they will closely intermesh with the teeth of the driving gear 12. It will be understood that these 115 gear teeth slots extend through the sleeve 36, body portion 34 and bearing sleeve 41 at the right hand end of holder 15.

120 It will be understood that sleeve 36, body portion 34 and sleeve 41 always rotate in unison, the latter sleeve being secured in any desired manner, as by a key (not shown) to the stub shaft 42 which extends to the right of the body portion 34 of holder 15. Secured to the sleeve 41, or preferably integral therewith, is a driving gear 43 which is adapted to drive the right hand holder when enmeshed with the driving gear 12. By reason of the slots 40 and 40^a (to be hereinafter described) it is possible to slide 125 130

both holders 15 and 14 to the left of the position shown in Figs. 1 and 2, since the before mentioned slots 40 and 40^a intermesh with the teeth of the driving gear 12 during 5 the sliding movement, and thereby the right hand holder 15 can be slid to a position to engage the gear 43 with the main driving gear 12. Since all parts of the right hand holder rotate in unison the timing of the 10 holder and driving gear will be correct when they are engaged.

Rotation preventing devices.—In order that slugs be replaced it is necessary that some means be provided for preventing the 15 rotation of the disengaged holder, otherwise the friction of the parts might be sufficient to rotate the holder, and this would be exceedingly dangerous to those in the vicinity of the machine. In order to prevent such 20 rotation of the disengaged holder the central slot of slots 40, which I will term 40^a, is extended through the parts of the left hand holder, including the sleeve 32, the body portion and sleeve 23. The slot 40^a also 25 extends through the face of this bearing sleeve 23 and annular member 28 of the right hand holder, and at these points the size of the slot is increased as shown by the notches at 45 and 46, Figs. 4 and 5. 30 This increase of size is necessary to permit the rocking of the sleeves and annular members to disengage the cap screws 26 and 27 from their respective notches. Engaging the slot 40^a at both sides of the machine 35 are toothed pieces 47 and 48. 47 is secured to the frame 10 and rests in the notch 45 of the bearing sleeve 23, when the left hand holder 14 is at "in". When in this position the toothed piece 47 does not interfere with 40 the rotation of the left hand holder, since sleeve 23 is freely rotatable with respect to the holder. When the right hand holder is out the notched piece 48, which is secured to the frame 11, extends up and engages the 45 slot 40^a of the right hand holder and thereby prevents its rotation. When the right hand holder 15 is "in" the toothed piece 48 rests in the widened notch 46 of the annular member 28 and thereby permits the rotation 50 of the right hand holder, since 28 is rotatable with respect to holder 15. At the same time toothed piece 47 is engaging the slot 40^a of the left hand holder and is preventing its rotation. 55 *Lock disengaging mechanism.*—By referring to Fig. 1 it will be understood that when holder 14 is "in" and locked it can only be released by swinging the left hand handle 20, and that when holder 15 is "in" and locked it can only be released by swinging the right hand handle 20^a. This would necessitate the operator walking around the machine to release the handle and thereafter push the mandrel or holder through the 60 machine. If this were done speed would be

diminished and the object of the invention defeated. I therefore provide means for releasing the holder from either side of the machine so that wherever an operator may be he can release the handle adjacent him or opposite from him. This mechanism is shown in Figs. 1, 2 and 4. Extending upwardly from the handle supporting pieces which are integral with sleeve 23 and annular member 28 are bent levers 50 and 51. 70 Lever 50 on holder 14 extends up and engages between two pins 53 which are carried on a link 54 which is slidably mounted on the printing machine frame. A crank arm 55 connects the end of link 54 with a shaft 56, which extends across the machine and carries at the opposite end a downwardly depending handle 57. The bent lever 51 of the right hand holder when in "in" position engages between similar pins 58 which 80 are carried on a sliding link 59. Link 59 connects at its end with a crank 60 which is secured to a cross shaft 61 carrying at its opposite end the downwardly depending handle 62. It will be seen that by manipulating the handles 57 and 62 that the bent levers 50 and 51 can be rocked thereby rocking sleeve 23 and annular member 28 and releasing the cap screws 26 and 27. In this 85 way it is possible to release the engaged slug 95 holder from either side of the machine.

In case the operator has any difficulty in alining the slots 40 with the driving gear 12 I provide means for swinging the holder bodily by manipulation of the handle 20^a. 100 This structure, although not absolutely necessary, permits the operator to swing the holder if the alining devices were broken or for any other desired reason. For this purpose I provide the following mechanism: 105 Annular member 28, as previously explained, is freely rotatable on the stub shaft 42 and is held in position by a collar, as shown in Fig. 6. This annular member 28 is provided with a post 70 which carries 110 a pivoted pawl 71 which extends over a normally outwardly spring pressed plunger 72. Directly under the end of this plunger, which extends through annular member 28, are a number of cups 73 in the gear 43. 115 These cups are arranged in circle on the side of this gear. By pressing inward on the handle 20^a (left hand handle) the nose 74 of the handle will rock the pivoted pawl 71 and depress the plunger 72 into engagement 120 with the cups in gear 43. Thereafter the swinging of the handle 20^a will be effective to rotate the right hand holder 15. This construction enables the operator of the machine to aline the holder without touching 125 the holder itself. The handle 20^a also gives more leverage for rotating the carrier. It is to be understood that my invention is not limited to the precise details described and illustrated, but is susceptible of various 130

embodiments. The terms used in the specification are also to be understood to be terms of description and not of limitation.

What I claim as my invention is particularly pointed out in the appended claims:

- 5 1. In a device of the class described, in combination, a plurality of composition carriers, said carriers being movable in the direction of their axes, means for securing composition to each of said carriers, and means for retaining said carriers in either of two axial positions whereby when in one position one carrier is in position for printing and the second carrier is in an accessible position for changing type and whereby 10 when in the other position the first carrier is accessible for changing type and the second mentioned carrier is in position for printing.
- 15 2. In a printing machine, in combination, a plurality of composition carriers axially aligned one with the other and movable in the direction of their common axis, means for securing composition to the said carriers, and means for retaining said carriers in either of two axial positions, said carriers when in one position placing one carrier in printing position and the other in an accessible position for changing composition and 20 when in the other position placing the last mentioned carrier in printing position and the first mentioned carrier in accessible position for changing composition.
- 25 3. In a printing machine, in combination, a composition carrying mandrel adapted to be shifted laterally in the plane of a printing machine, means for independently rotating a plurality of means for securing independent pieces of composition to said carrier, said means being independent of each 30 other, means for retaining said mandrel in either of two positions whereby one or the other of the sets of composition is brought into printing position and whereby the other 35 set of composition is brought to an accessible position for replacement or cleaning.
- 40 4. In a printing machine, in combination, a composition carrying mandrel adapted to be shifted laterally in the frame of a printing machine, said mandrel having two axially aligned portions independently rotatable with respect to each other, and means for shifting said mandrel to engage and disengage one portion with a driving means 45 and to disengage and engage the other portion with the driving means.
- 50 5. In a printing machine, in combination, a composition carrying mandrel adapted to be shifted laterally in the frame of a printing machine, said mandrel having two axially aligned portions independently rotatable with respect to each other, means associated with each of the aforesaid portions of the mandrel for securing composition 55 thereto, and means for shifting said man-

drel to engage and disengage one portion with a driving means and to concurrently disengage and engage the other portion with the driving means.

6. In a printing machine, in combination, 70 a plurality of independently rotatable composition carriers, means for detachably securing composition thereto, a driving means and manually operable means for selectively engaging either of said carriers with the 75 driving means.

7. In a printing machine, in combination, a plurality of independently rotatable composition carriers, means for detachably securing composition thereto and means for 80 releasing the said composition securing means whereby the composition may be readily removed from the carrier, a driving means, means for selectively engaging either of said carriers with the driving means, said 85 means having provisions for rotating one carrier and at the same time for disengaging the other carrier.

8. In a printing machine, in combination, 90 a plurality of independently rotatable composition carriers, means for detachably securing composition thereto and manually operable means for releasing the composition securing means whereby the composition may be readily released and replaced, 95 a driving means, means for selectively engaging either of said carriers with said driving means, and means associated with said carriers for timing said carriers with the driving means upon the engagement of 100 said carriers with the driving means.

9. In a printing machine, in combination, 105 a plurality of independently rotatable slug holders, driving gears thereon, slug securing devices on said holders, a driving gear, means for shifting said holders in position to engage or disengage their respective gears with the driving gear, and means on said carriers to properly align the gears and the driving gear whereby correct angular alignment and timing is secured between the engaged gear and its associated holder and the driving gear.

10. In a printing machine, in combination, 115 a frame, type carriers movable laterally in said frame, handles on said carriers for shifting them in and out of the frame, type securing means on said carriers and means operable by the handles to disengage the type and permit their replacement, 120 sleeves revolvably mounted on said carriers and means associated with said sleeves and handles for securing the carriers in position on the frame but at the same time permitting their rotation therein.

11. In a printing machine, in combination, 125 frame, type carriers movable laterally in said frame, a handle on said carriers for shifting them in and out of the frame, type securing means on said carriers and means 130

- operable by the handles to disengage the type and permit their replacement, sleeves revolubly mounted on said carriers and means associated with said sleeves and handles for securing the carriers in position in the frame but at the same time permitting their rotation therein, and means associated with one of said handles for securing the coöperating carrier and handle together whereby said carrier may be turned to proper position prior to its being slid into the frame of the machine. 5
12. In a printing machine, in combination, a plurality of composition carriers, said carriers being movable in the direction of their axes, means for securing composition to each of said carriers, means for retaining said carriers in either of two positions, means for sliding said carriers axially when disengaged from the aforesaid detaining means, a common driving means, and means associated with the carriers for alining and timing the carriers when they are slid axially, said means being adapted to cause the composition on one holder to be placed in proper angular relation to the driving means. 10
13. In a printing machine, having a frame, in combination, a plurality of composition holders, said holders being movable in the direction of their axes into and out of the frame, means associated with the holders and the frame for securing said holders in in or out position with respect to said frame, means for securing composition to said holders, means for sliding said holders in the frame when disengaged from the aforesaid first mentioned securing means, a driving means, said carriers being engaged with said driving means when they are in in position and disengaged therefrom when in out position, and an alining and timing means for causing the engaged carrier to be properly timed and alined with the driving means when in in position. 15
14. In a printing machine, in combination, a plurality of independently rotatable composition carriers, means for detachably securing composition thereto and means for operating said composition securing means whereby the composition may be readily replaced, a driving means, means for selectively engaging one of said carriers with said driving means, and means for alining and timing the driving means and the said carriers with respect to each other. 20
15. In a printing machine, in combination, a plurality of independently rotatable composition carriers, means for detachably securing composition thereto and means for operating said composition securing means whereby the composition may be readily replaced, a driving means, means for selectively engaging one of said carriers with said driving means, and means for pre- 25
- venting the rotation of one carrier which is out of engagement with the driving means whereby the type thereon are readily accessible for replacement or cleaning. 30
16. In a printing machine, in combination, a plurality of independently rotatable composition carriers, means for detachably securing composition thereto, a driving means, means for selectively engaging one of said carriers with said driving means, and means for preventing the rotation of one carrier which is out of engagement with the driving means, the said rotation preventing means being adapted to aline the disengaged carrier with the driving means when it is engaged therewith. 35
17. In a printing machine, in combination, a frame, a plurality of independently rotatable composition carriers, means for securing either of said carriers in position in the said frame, means for disengaging said retaining means, said means being operable from the opposite sides of the frame whereby the operator of the machine may disengage a carrier having its retaining means at the opposite side of the frame. 40
18. In a printing machine, in combination, a frame, a plurality of independently rotatable composition carriers, a plurality of retaining means for retaining said carriers in either of two axial positions in said frame, and means for disengaging the engaged retaining means, said means being operable from the side of the machine opposite to that of the engaged retaining means whereby an operator on either side of the machine may release the engaged carrier and slide the other carrier to operating position within the frame. 45
19. In a printing machine, in combination, a frame, a plurality of independently rotatable composition carriers, means for retaining said carriers in either of two axial positions whereby when in one position one carrier is in position for printing and the second carrier is in accessible position for changing type and whereby, when in the other position, the first carrier is accessible for changing type and the second mentioned carrier is in position for printing and means operable from either side of the machine for releasing the engaged carrier whereby an operator may release the carrier from either side of the machine. 50
20. In a printing machine, in combination, a plurality of independently rotatable axially alined composition carriers, means for detachably securing composition thereto, a driving means, and means for sliding the axially alined carriers and thereby engaging either of said carriers with the driving means and disengaging the other of the carriers. 55
21. In a printing machine, in combination, a machine frame; a plurality of inde- 60

pendently rotatable axially alined composition carriers suitably journaled in said frame; means for shifting said carriers in unison to either of two axial positions, said carriers, when in one position, being disposed with one carrier without the machine in accessible position for changing the type thereon, and with the other second carrier in printing position within the machine frame, 10 said carriers when in the opposite position, being disposed with the first mentioned carrier in printing position within the frame and the second mentioned carrier without the frame in accessible position for changing the type thereon.

22. In a printing machine, in combination, a frame; a plurality of independently rotatable axially shiftable composition car-

riers having provisions for securing type thereto; a carrier shifting means for axially shifting the said carriers within and without the machine frame, one carrier being without the frame in accessible position for changing the type thereon when the other carrier is within the frame and in printing 25 position, said carriers being adapted to reverse their respective positions within and without the machine frame when the shifting means is operated.

In testimony whereof I affix my signature 30 in the presence of two subscribing witnesses.

HOWARD F. MARSTON.
